UNITED STATES PATENT OFFICE.

STEPHEN A. ELLETT, OF ELMIRA, NEW YORK, ASSIGNEE TO ECLIPSE MACHINE COMPANY, OF ELMIRA, NEW YORK, A CORPORATION OF NEW YORK.

ENGINE STARTER.

Application filed March 8, 1918. Serial No. 280,313.

To all whom it may concern:

Be it known that I, STEPHEN A. ELLETT, a citizen of the United States, residing at Elmira, in the county of Chemung and State of New York, have invented certain new and useful Improvements in Engine Starters, of which the following is a specification.

My invention relates to starters for engines, more particularly internal combustion engines, and the object thereof is to produce a novel, efficient and compact construction of starter whose features of advantage and utility will be apparent from the description hereinafter given.

In the drawing Fig. 1 is a sectional elevation of a starter embodying my invention; and Fig. 2 a section on the line 2-2 of Fig. 1.

Referring to the particular embodiment of my invention as herein shown, the prime mover is in the form of an electric motor indicated at A, and the drive or transmission which is normally disengaged from the engine member such as the fly wheel B is combined with the structure of such motor. In the present instance the motor-driven or power shaft is the hollow armature 1 of the electric motor which is adapted to positively drive a driven shaft 2 of the drive or transmission. This latter shaft extends entirely through the armature and projects from the opposite ends thereof. One of the projecting ends which is here the right-hand end is provided with screw threads 3 on which is mounted a driving member in the form of a pinion 4 screw-threaded on such screw threads for longitudinal movement of its shaft and also rotary movement therewith. The remainder of the driven shaft 2 is substantially plain and has a positive driving connection with the armature which connection is here in the form of splines and grooves, the splines 5 being preferably in the armature and the grooves 6 in the driven shaft. This operating connection is such as to cause a positive rotary motion between the two shafts but to permit a longitudinal movement of the driven shaft with respect to the driving shaft.

The driven shaft is provided at its outer left-hand end with a nut 7 between which and the adjacent end of the armature there is interposed a coiled spring 8 which tends to hold the driven shaft towards the left in the normal position shown. This position

is determined by the contact of the shoulder 9 at the left-hand end of the screw-threaded portion against the outer end of the thrust bearing 10 mounted at the right-hand side of the armature.

Describing the mode of operation and starting with the parts in their normal position as shown in Fig. 1, when the electric motor is rotated the driven shaft 2 is correspondingly rotated with the result that the pinion 4 is advanced inwardly towards the motor and longitudinally of its shaft and into engagement with the teeth of the fly wheel B. The pinion is arrested in its longitudinal movement when in full mesh by the contact of its inner end against the shoulder 10⁴ of the thrust bearing 10, such pinion being counter-bored at this end so as to fit over the shoulder 9 and make the contact stated. Thereupon the pinion partakes of the rotary movement of its shaft and rotates the fly wheel. When the engine has started on its own power the pinion is automatically demeshed and returned to its normal or home position as shown, the same being stopped at such home position by means of the abrupt ends 3⁵ of the screw threads which are contacted by the pinion threads in the usual manner.

In the event that the pinion teeth and fly wheel teeth should not register but should abut end to end, such impact is cushioned by reason of the yielding longitudinal movement of the driven shaft 2 which, under such condition, is permitted to move longitudinally to the right against the tension of the spring 8 until the pinion is slightly rotated in order to bring its teeth into register and mesh with the fly wheel whereupon the spring returns the shaft to its normal position. This spring also serves as a yielding driving connection in the driving operation, inasmuch as when the pinion then bears against the thrust bearing, the tendency of the driving load is to pull the grooved shaft 2 through the hollow armature. As this tendency is resisted by the spring, there is thus provided a yielding driving connection through the utilization of this compression spring.

I claim:

1. A drive or transmission for an engine starter comprising, in combination, an electric motor having a hollow rotatable armature shaft, a driven shaft arranged within

- 5 said armature shaft and having a spline and groove connection therewith for positive rotary movement between the two shafts and a relative longitudinal movement there-
6 of, the driven shaft being of such length that its opposite ends project beyond the ends of the armature shaft, a driving mem-
7 ber mounted on one of the projecting ends of said driven shaft for longitudinal move-
8 ment thereof and rotary movement there-
9 with, and resilient means positioned on the opposite projecting end of said driven shaft for resisting longitudinal movement of the same in one direction.
10 15. 2. A drive or transmission for an engine starter comprising, in combination, an electric motor having a hollow rotatable armature shaft, a driven shaft arranged within said armature shaft and having a spline and groove connection therewith for positive rotary movement between the two shafts and a relative longitudinal movement thereof, the driven shaft being of such length that its opposite ends project beyond the ends of the armature shaft, and one of said projecting ends being provided with screw threads, an anti-friction thrust bearing mounted on the motor through which the driven shaft has a limited longitudinal movement, a driving member mounted on the threaded portion of the driven shaft for longitudinal movement thereof and rotary movement therewith, and a coil spring positioned on the opposite projecting end of said driven shaft for resisting longitudinal movement of the same in one direction.
